UNITED STATES PATENT OFFICE.

RUDOLPH C. KRUSCHKE, OF DULUTH, MINNESOTA.

HUNTER'S LAMP.

SPECIFICATION forming part of Letters Patent No. 711,871, dated October 21, 1902.

Application filed November 23, 1901. Serial No. 83,400. (No model.)

To all whom it may concern:

Be it known that I, RUDOLPH C. KRUSCHKE, a citizen of the United States, residing at Duluth, in the county of St. Louis and State of Minnesota, have invented certain new and useful Improvements in Hunters' Lamps, of which the following is a specification, reference being had therein to the accompanying drawings.

10 My invention relates to improvements in acetylene-gas lamps, and refers particularly to a gas-lamp for the use of hunters; and the object of my invention is the production of a lamp for this purpose which will be inexpensive, light in weight, easily applied, and thoroughly practical.

With these objects in view my invention consists of a lamp embodying novel features of construction and combination of parts, substantially as disclosed herein.

Figure 1 represents a view of a human figure with my lamp applied. Fig. 2 represents a perspective view of the lamp detached.

The lamp comprises the reservoir A, the burner portion, and the tube D. The reservoir A is provided on one side with the clip B, which connects the water and gas chambers of the lamp and forms the means for attachment of my lamp to the belt C, used for carrying the ammunition. Secured vertically to the generating or gas chamber and leading therefrom is the supply-tube D, which extends upward and passes through the guide E on the securing-band F, which fastens the device to the hat around the same, and the tube leads into the reflector G, which is secured to the hat band or fastener, and the reflector is provided with the brackets G', which are secured to the curved plate G², said plate being rigidly fastened to the front of the hat-band, and the reflector is provided with the chimney H for carrying off the heat from the head. The reflector is provided with a hinged door having a suitable glass.

The chimney of my lamp is of peculiar construction and comprises the outer chimney-tube H and the inner tube H', forming an air-space J between the tubes, which keeps the chimney cool and also keeps the heat away from the hat-band, and consequently the hat, and thus the head of the user cannot be affected by the heat of the lamp.

From the foregoing description and drawings it is evident that I provide a lamp which can be easily carried by the hunter and that the light is so placed as to give the best results as to illuminating and also that the lamp is light in weight and of small size, can be produced at a fair price, and will prove efficient and practical.

I claim—

1. In a hunter's lamp, the combination of a band to be secured to a hat or head-covering, a plate secured to the front of said band, a reflector connected to the plate, a double-walled chimney on said reflector, a burner in the reflector, a supply-tube leading from the burner to the reservoir for combustible fluid, a guide securing the tube to the band, and means for securing the reservoir to the body.

2. In a hunter's lamp, the combination of a band arranged for attachment to a hat or head-covering, a reflector connected to said band, a chimney on the reflector having double walls forming an air-space, a burner in the reflector, a tube leading from the burner, a reservoir for combustible fluid to which said tube leads and a guide on the hat-band for said tube.

In testimony whereof I affix my signature in presence of two witnesses.

RUDOLPH C. KRUSCHKE.
